TUNNEL KILN

Edward Van der Pyl, Holden, Mass., assignor to
 Norton Company, Worcester, Mass., a corporation of Massachusetts

Application January 18, 1949, Serial No. 71,445
 In Canada December 28, 1948

8 Claims. (Cl. 13—20)

1

The invention relates to tunnel kilns.

One object of the invention is to provide a tunnel kiln particularly adapted for vitrifying large massive pieces such as pulpstone blocks or segments. Another object of the invention is to provide a tunnel kiln particularly adapted for vitrifying large pieces of ware which are thick in every dimension.

Another object of the invention is to provide an electric tunnel kiln which delivers radiant energy at the top, bottom and both sides of the tunnel. Another object of the invention is to provide a construction for a tunnel kiln having electrical resistor rods both horizontally and vertically through the tunnel. Another object of the invention is to place four banks of resistor rods as close as possible to the ware being vitrified both above, below and on each side of the ware in the tunnel of a kiln, thus greatly accelerating the vitrification of massive pieces of ware. Another object of the invention is greatly to accelerate the vitrification of large massive pieces of ware such as pulpstone blocks. Another object of the invention is to provide a tunnel kiln capable of vitrifying a relatively large mass of ware per year as compared with the mass of the kiln.

Another object of the invention is to provide transportation means for ware through a tunnel kiln of unique characteristics in that only batts need be used and except in the firing zone and adjacent thereto anti-friction devices are employed, but in the firing zone there is nothing but refractory material, no metal parts being present in the firing zone.

Other objects will be in part obvious or in part pointed out hereinafter.

In the accompanying drawings illustrating one of many possible embodiments of the mechanical features of this invention,

Figure 1 is a side elevation of the kiln on a reduced scale.

Figure 2 is a side elevation of the firing zone of the kiln on a scale larger than that of Figure 1.

Figures 3 and 4 are cross sectional views taken respectively on the lines 3—3 and 4—4 of Figure 2, but showing the parts on a larger scale.

Figures 5, 6 and 7 are cross sectional views on the same scale as Figures 3 and 4, and taken on the lines 5—5, 6—6 and 7—7 respectively of Figure 1.

The kiln as a whole is identified by the numeral 20 and comprises a steel box having the shape of a parallelepiped. This steel box and its contents are supported by legs 21. At the entrance end of the kiln there is a front wall 30 comprising a large piece of steel plate. At the exit end of the kiln there is a similar rear wall 32. Extending through the kiln from end to end, that is from the front wall 30 to the rear wall 32, is a long tunnel 35. To operate the kiln a great number of

2

batts 80 are provided and these batts 80 may have the shape shown in Figures 3 to 7 inclusive. There is a kiln bottom 400 and a kiln top 401 and both of these may be made of steel plate. There are kiln side walls 402 and these likewise may be made of steel plate.

The legs 21 are each formed of a pair of angle irons which extend all the way to the top of the kiln thus bracing the side walls 402. Additional vertical angle irons 404 may be provided between the legs 21 to furnish further bracing. On each side of the kiln there is a long series of longitudinal irons 405 at an upper level and a short series of longitudinal irons 406 at a lower level. At the firing zone of the kiln are short vertical angle iron braces 407. Across the top of the kiln are angle iron braces 408 and across the bottom of the kiln are angle iron braces 409.

This entire metal structure is preferably held together by welding and constitutes a strong box. It is preferably rectangular in any cross section but as will be seen from Figure 1 the side elevation is a non-rectangular parallelogram the angles at the end being slightly more and less than 90°, namely about 2° more and less. Thus the entire kiln 20 is inclined downwardly at a slight inclination from the front wall 30 to the rear wall 32 and this is more particularly to provide a slight draught in the tunnel 35 of the kiln. Therefore the sectional views Figures 3 to 7 are not quite vertical sectional views being at an incline of about the same 2° to the vertical. In constructing the refractory structure now about to be described, rectangular parallelepipedal bricks 410 are used and the supporting bottom level of bricks 410 are placed with side faces thereof right on the kiln bottom 400.

The refractory structure of the kiln comprises this bottom level of bricks 410 herein shown as one brick high, side walls of bricks 411, a kiln bottom structure 412 which may be three bricks high as shown, and, except where cut away as will hereinafter appear, is a parallelepiped, courses of tunnel side bricks 413 shown in each section as one brick on each side, courses of up-ended bricks 414 adjacent the walls 411, there being one brick 414 on each side at any section, tunnel arch bricks 415, one at every section, between the courses 414, and a parallelepipedal kiln top layer of bricks 416 between the walls 411 and above the courses 414 and the tunnel arch bricks 415. This parallelepipedal kiln top layer 416 may be two bricks high as shown. The tunnel arch bricks 415 form the top of the tunnel 35 and they rest upon the side bricks 413 which as shown form the sides of the tunnel 35, and the bottom of the tunnel 35 is formed by the kiln bottom structure 412.

Between the steel side walls 402 and the brick side walls 411 on each side is loose refractory

material 420 as further heat insulation. This loose refractory material 420 is also preferably placed between the kiln top layer of bricks 416 and the kiln top 401. A material which is very satisfactory to use for this loose filling is finely divided diatomaceous earth which has high thermal resistance.

Referring now to Figure 1, it is convenient to describe the kiln 20 as divided into bays, each bay having the volume of kiln bounded on one end by the plane of a pair of legs 21, one on each side and on the other end by the plane of an adjacent pair of legs 21. Half a bay is described as the volume of the kiln bounded by the plane of a pair of legs 21 and the plane of a pair of vertical angle irons 404 or angle iron braces 407. The foregoing is merely for convenience in referring to various parts of the kiln because there is no boundary line between bays or half bays in the tunnel 35 and some bricks may be partly in one bay and partly in another bay.

Referring now to Figures 3 to 7 inclusive, extending the entire length of the tunnel 35 are parallel refractory members 421, there being a continuous succession of these members 421 on each side of the tunnel 35 and each succession of members 421 extending without a break from the entrance end to the exit end of the tunnel 35. These refractory members 421 are preferably made of self-bonded aluminum oxide and they are thus highly refractory and resistant to wear. Located in the grooves in these members 421 are rods 425 which are also preferably made of self-bonded aluminum oxide and therefore also are highly refractory and resistant to wear. There is a continuous succession of rods 425 on each side of the tunnel 35 and the rods 425 are in contact with each other. These rods 425 are cylindrical but their ends are tapered. The batts 80, which are preferably made of vitrified silicon carbide, also a very refractory material, ride upon these rods 425 in the hotter bays. We have found that silicon carbide batts riding upon aluminum oxide rods is a highly practical answer to the problem of moving material to be vitrified through the firing zone of a kiln for the rods 425 and the batts 80 can withstand temperatures above 1300° C. in an oxidizing atmosphere during repeated cycles and furthermore are resistant to heat shock, and both parts are resistant to wear and the coefficient of sliding friction is not too high. But to reduce the total friction I prefer, as shown in Figures 6 and 7, to support the batts 80 by means of rollers 430 in the cooler bays. The rollers 430 are trunnion rollers and are journaled in channel irons 432, each channel iron 432 being made out of three parts suitably secured together. These channel irons 432 are found in the following bays reading from left to right, Figure 1: bay No. 1, bay No. 7, bay No. 8 and the first half of bay No. 9 which is the final bay. It will be seen that bay No. 3 and bay No. 4 are the firing zone bays; bay No. 1 and bay No. 2 are the preheating zone bays, but bay No. 2 is quite close to the firing zone so there are no channel irons 432 and rollers 430 in bay No. 2. Similarly bays Nos. 5 and 6 are annealing zone bays but they are also so close to the firing zone that no channel irons 432 with rollers 430 are placed therein. The remainder of the annealing zone comprises bays 7, 8 and 9 and the channel irons 432 with rollers 430 can be placed the entire length of this part of the annealing zone but there is an advantage in omitting them in the

final half bay of the kiln which will presently be explained.

In order that the rollers 430 may support the batts 80, the rods 425 which are alongside of rollers 430 are undersized rods. For example the rods 425 wherever there are no rollers 430 may be 1 1/4" in diameter and the rods 425 where there are rollers 430 may be only 1" in diameter. The rollers 430 are of such height that they support the batts above the tunnel bottom at the same height as do the full diameter rods 425. It will be noted that the rods 425 are located under grooved enlarged marginal portions 435 of the batts 80 whereas the rollers 430 are located just inside these grooved enlarged marginal portions 435. The channel irons 432 are just inside of the refractory members 421 and a continuous set of channel irons 432 on one side is parallel to a continuous set of channel irons 432 on the other side. Thus the refractory members 421 extend from end to end of the tunnel 35 but the channel irons 432 and rollers 430 are found only in bay 1, bay 7, bay 8 and the first half of bay 9. In the last half of bay 9 the rods 425 are full size and support the batts 80 and the reason for this is that if the batts 80 at the exit end of the kiln were supported by rollers 430, there would be nothing to stop the motion of the batts once started especially in view of the slight downgrade, so to hold the batts in the annealing zone of the tunnel a frictional brake is applied to them in the final half bay thereof.

The reason for providing rods 425 supported by members 421 in those bays where there are channel irons 432 with rollers 430 is that thereby a whole line of rods 425 can be removed from the kiln merely by pushing them, thus to replace rods 425 when finally they become worn too much. Also in this manner the rods can be rotated from time to time to distribute the wear merely by removing them and replacing them. Therefore undersized rods are provided where the rollers support the batts and everywhere there are rollers 430 there should be undersized rods 425 but wherever there are no rollers 430, the rods 425 should be of full size. The reason why the ends of the rods 425 are tapered is so that a batt 80 can ride across a rod junction without catching.

For the bricks 410 and 416 inclusive any refractory material of adequate strength and thermal resistance may be used but I have found that a very satisfactory material is porous kaolin which makes a light weight brick that is therefore easy to handle, which makes a somewhat soft brick, which is therefore easy to cut, which is sufficiently refractory to withstand a temperature of more than 1300° C., which has a high thermal resistance, and which is relatively inexpensive.

Referring now to Figures 2, 3 and 4, the firing zone of the kiln which comprises bays No. 3 and No. 4 in this embodiment of the invention has two banks of rod resistors 440 extending horizontally through the kiln and two banks of rod resistors 440 extending vertically through the kiln. The horizontal rod resistors 440 pass through refractory bushings 441 which extend from the outside of the wall 402 to the outside of the wall 411 on each side of the kiln; the vertical rod resistors 440 pass through refractory bushings 442 which extend from the outside of the kiln top 401 through the material 402 to the top of the bricks of the kiln top 416, and at the bottom these vertical rods 440 pass through refractory bushings 443 that extend from the underside of the kiln bottom 400 to the top of the

supporting bottom level of bricks 410. From the bushings 441 at one side to the bushings 441 at the other side the upper bank of horizontal rods 440 extend through the side walls 411, the upended bricks 414, and each one extends through one tunnel arch brick 415. Comparing now Figures 3 and 4 with Figure 5 for example, it will be seen that the tunnel arch bricks 415 in the firing zone have ceiling vaults 445 permitting a length of each horizontal rod resistor 440 of the upper bank to extend clear of the brick work and thus to heat the tunnel 35 at the firing zone by direct radiation. Likewise comparing Figures 3, 4 and 5, it will be seen that in the firing zone one longitudinal course of bricks of the kiln bottom structure 412 is omitted forming a floor trench 446 across which extend naked rods 440 of the lower bank of horizontal rods. These rods 440 of the lower bank of horizontal rods extend from the bushings 441 on one side to the bushings 441 on the other side, through the walls 411 and the kiln bottom structure 412 and across this floor trench 446 where they provide direct radiation in the tunnel 35 especially to the underside of the batts 80.

The vertical rod resistors 440 extend in parallel banks, one on each side of the tunnel 35, from the bushings 443 at the bottom through the kiln bottom structure 412, then through embrasures 447 formed by cutting away the courses of side bricks 413 in the firing zone, then the rods 440 extend upwardly through the tunnel arch bricks 415 and through the kiln top 416 to the upper bushings 442. So that the vertical rods 440 will not drop out of the kiln they are supported by brackets 450 attached to the kiln bottom 400 and insulating pads 451 are provided to prevent short circuiting of the rods 440.

These rod resistors 440 may be of any type capable of being heated to a temperature of above 1400° C. by the passage of electric current therethrough and having a reasonable life at such temperatures or, in case ware of less refractory characteristics than the usual grinding wheel is to be vitrified in the kiln, the rods 440 might be of a type capable of being heated only to lower temperatures. For vitrifying grinding wheels and pulpstone blocks and the like the best rod resistors now known to me are silicon carbide resistor rods. These are made of recrystallized silicon carbide and they are cold ended, that is they have cold ends of low resistance. For example, silicon carbide fines of several different grit sizes and of the purer grades are mixed with a small quantity of sodium silicate then this material is tamped into an iron pipe lined with paper and having holes in its wall, then the pipe is placed in an oven to drive off the water from the sodium silicate, the baked rod of bonded silicon carbide is removed and it is then recrystallized by passing electric current through it and, in certain cases, it may be given a further heat treatment at the recrystallizing temperature in an induction tube furnace made of graphite. Later on the rod is cold ended by causing superheated liquid silicon to permeate the pores of the end portions. The horizontal rods 440 should have cold ends extending from the very ends of the rods to the vault 445 in the upper bank and to the trench 446 in the lower bank, and the vertical rods 440 should have cold ends extending from the very ends of the rods to the embrasures 447. For it is undesirable to liberate heat in the bricks of the kiln or near the bottom 400, the top 401 or near the sides

402. It will thus be seen that the heat provided by the electrical resistor rods 440 is liberated almost entirely in the vault 445, in the trench 446 and in the embrasures 447.

The rod resistors 440 are connected to electric power in a manner well known to those skilled in the art, so no diagram of the electric circuits nor description thereof need be provided herein. The rod resistors should be electrically heated to a high enough temperature so that the firing zone of the kiln (bays 3 and 4) will be at vitrifying temperature to vitrify the particular ware involved. In the case of large pulpstone blocks 450 this temperature should be of the order of 1200° C. or 1300° C. in the firing zone in the tunnel 35. From Figures 3 and 4 it will be seen that the rods 440 radiate heat directly upon the top and upon the sides of the blocks 450 and the lower bank of horizontal rods 440 radiate heat directly to the bottoms of the batts 80. The batts 80 are thin and silicon carbide is a good heat conductor, so the blocks 450 are heated from four sides by direct radiation and thus the heat penetrates evenly. The vitrification of massive pieces of ware such as the blocks 450 has always been a problem and in conventional kilns has taken several days. With the kiln of this invention large pulpstone blocks 450 can be vitrified in ten hours counting from the time a cold block 450 in a "green" state is rammed into the tunnel 35 by a ram, not shown, to the time it emerges from the tunnel 35 fully vitrified.

In order that the operator of the kiln may have knowledge of the temperature of the various bays of the kiln in the tunnel 35, pyrometers may be provided at intervals along the kiln 20 but it has not been thought necessary to show these in the drawings. The operator can change the temperature in the firing zone or parts thereof by adjusting the current flow to the rods 440 or to particular groups thereof, all in a manner well known and automatic controls may be provided if desired. The temperatures of the various bays of the preheating and annealing zones can be controlled by the operator by means of various dampers in flues as will now be described.

The "green" pulpstone blocks 450 or other ware usually contain combustible organic material as a temporary binder; this starts vaporizing even as early as bay No. 1 and burns in subsequent bays of the preheating zone and finally becomes completely burned out at some point in the firing zone and therefore it is desirable to carry off the gases produced by this material and especially to provide enough oxygen so that little if any carbon residue will remain. So therefore the kiln 20 is provided with a chimney 455 and this, as shown in Figure 6, is connected to a chimney flue 456 which is integral with a pair of flues 457 extending from the flue 456 at first angularly and then straight downward to a level below the bottom of the tunnel 35, there being one flue 457 on each side of the kiln. These flues 456 and 457 may be built into one piece out of refractory sheet metal such as a nickel-iron-chromium alloy of 60 nickel, 24 iron and 16 chromium, inserted in place after certain bricks have been laid some of these being cut, and thereafter the other bricks are suitably cut and laid around and inside of the flues 457 as shown in Figure 6.

Also made of the same sheet metal and connected to the flues 457 are horizontal connecting passages 458 extending above cut tunnel side wall bricks 413 to the inside of the tunnel 35. These passages 458 collect the gases in the tunnel 35

and deliver them to the flues 457 and thence they go through the chimney flue 456 and up the chimney. Any gas, mostly air, flowing in the tunnel 35 under the batts 80 is collected by a horizontal passages 459 connected to both flues 457 at the bottom thereof and having an opening into a well 460 in the bottom of the tunnel 35 like the trench 446. This passage 459 may be formed by sheet metal of the same kind connected to the flues 457. The flues 457 at the bottom extend right out to and through the walls 402 of the kiln and are closed by removable plates 461. Removal of the plates 461 allows easy access to the inside of the tunnel 35 for any purpose. There are also removable plates 462 on the sides of the kiln as shown in Figure 1—inside of these plates the bricks may be shaped for ready removal, also for access to the inside of the tunnel 35 in various bays. Such access is desirable in case of a smash in the tunnel which, however, rarely occurs.

Referring now to Figure 7, a flue 465 is connected to flues 466 which extend over and down the sides of the kiln and are connected to transverse passages 467 and 468. The flues 466 form a U as shown and they as well as the passages 467 and 468 can be made of sheet steel because the temperature at this part of the kiln is not so high. The passages 467 extend through the side walls 402, the side walls 411, and the side bricks 413 to the tunnel 35 above the rods 425. The passages 468 extend through the side walls 402, the side walls 411 and the kiln bottom structure 412 and are connected to a well 460 in the bottom of the tunnel 35. As shown in Figure 1, I provide slide dampers 470 and 471 to control the amount of air flowing from the upper part of the tunnel 35 and from the lower part of the tunnel 35 respectively into the flues 466.

The flue 465 is shown in Figure 1 and connects the flues 466 to the flue 456 and so to the chimney 455. There is preferably a slide damper 472 in the flue 465 to control the amount of gases going up the flues 457 and a rotatable damper 473 in the chimney for overall control. The flues 465, 466 and passages 467 and 468 constitute back draught means so that the suction created by the heat in the tunnel and the stack effect of the chimney 455 can be prevented from drawing too much air along the tunnel 35 in the annealing zone. There should be a small flow of air into the preheating zone of the kiln, preferably moving into bay No. 2, to provide oxygen for burning out the organic matter in the ware, for most ware contains organic matter as a temporary binder. It has been found that the organic matter in the "green" ware provides, in burning a significant amount of heat. It is desired that this organic matter be burned rather than merely volatilized in order to eliminate carbon deposit in the ware.

So far as the present invention is concerned, the batts may be propelled through the tunnel continuously at slow speed or intermittently by ramming a batt 80 or two or more batts 80 at a time into the tunnel 35, but at infrequent intervals, and any suitable mechanism may be used for this purpose. Automatic batt feeding and discharging mechanism for ramming batts from time to time into the tunnel 35 at the front wall 30 and removing them from the exit end of the kiln at the wall 32 is disclosed in a copending application filed by myself and George N. Jeppson on May 10, 1947, Serial No. 747,169, now Patent No. 2,523,025, granted September 19, 1950, and this mechanism may be profitably used with the kiln of this invention or an improvement

thereon disclosed in a copending application filed by myself and George N. Jeppson on January 28, 1949, Serial No. 73,312, may likewise be used.

It will thus be seen that there has been provided by this invention a tunnel kiln in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. A tunnel kiln comprising refractory bricks forming a structure which has one dimension of great length compared with others and forms a tunnel which has a vault in the top, a trench in the bottom and a pair of embrasures at the sides, said vault, said trench and said embrasures being located at the firing zone of the tunnel, a pair of sets of stationary parallel refractory rods in said tunnel located, in said firing zone, above said trench, below said vault and inside of said embrasures, a continuous shelf of refractory batts resting on said rods and slidably thereon, and silicon carbide electrical rod resistors in the vault, in the trench and in each of the embrasures the silicon carbide resistors in the embrasures extending completely through the kiln from the top to the bottom thereof, whereby a ram can propel the batts in a long line of batts on the refractory rods through said tunnel and between said electrical rod resistors.

2. In a kiln, a refractory structure forming a long tunnel having, in a firing zone thereof, a vault in the top, a trench in the bottom and a pair of embrasures in the sides, a refractory support in said tunnel comprising a pair of sets of stationary refractory rods each set being parallel to the other set and there being a substantial space between the sets and the rods being located above the trench, below the vault and between the embrasures, silicon carbide electrical rod resistors in the vault, in the trench and in the embrasures the silicon carbide resistors in the embrasures extending completely through the kiln from the top to the bottom thereof, the electrical rod resistors in the trench and in the embrasures being spaced from the refractory rods by a distance no greater than the distance between the sets.

3. In a tunnel kiln, a refractory structure forming a long tunnel having, in a heating zone spaced from the ends of the tunnel a vault in the top, a trench in the bottom, and embrasures in the sides, a plurality of silicon carbide electrical rod resistors extending through and across said tunnel in the trench, a plurality of silicon carbide electrical rod resistors extending through and across said tunnel in the vault, a plurality of silicon carbide electrical rod resistors extending from the top of the kiln to the bottom thereof through each of the embrasures, a straight stationary refractory rod support for batts on one side of the tunnel and extending through the heating zone above the trench, below the vault and adjacent one embrasure, a straight stationary refractory rod support for batts parallel to the first named straight refractory rod support for batts located on the other side of the tunnel and also above the trench, below the vault and adja-

cent an embrasure, and refractory batts resting upon said supports slidable therealong.

4. A tunnel kiln comprising a refractory structure forming a long tunnel, a heating zone intermediate the ends of said tunnel said heating zone having a vault, a trench and a pair of embrasures and said heating zone having a plurality of silicon carbide electrical rod resistors extending through the trench, having another plurality of silicon carbide electrical rod resistors extending through the vault, each of said rod resistors in each of the trenches and the vault extending across the tunnel from side to side thereof, and said tunnel having a plurality of silicon carbide electrical rod resistors in each of said embrasures extending from the top of the kiln to the bottom thereof, and said heating zone having stationary refractory batt supporting members in the lower part of said tunnel just above the plurality of electrical rod resistors in the trench, said batt supporting members extending lengthwise of the tunnel on either side thereof adjacent the embrasures and parallel to each other, refractory flat batts extending from end to end of the tunnel not only in the heating zone thereof but also in the other parts of said tunnel and, in the heating zone, being supported by the refractory supporting members, said batts therefore being above the plurality of electrical rod resistors in the trench and also being below the plurality of electrical rod resistors in the vault and there being a clear space between the rod resistors in the trench and the undersides of the batts, said tunnel being by the batts divided into an upper part and a lower part to reduce convection and provide for controlled heating and vitrification, the batts constituting supports for ware to be vitrified and there being a clear space in the heating zone from the top of the batts to the rod resistors in the vault whereby the ware is heated by direct radiation therefrom on the top and also by direct radiation to the underside of the batts and then through the batts, each batt extending across the tunnel from the refractory supporting member on one side to the refractory supporting member on the other side, supporting members on the sides of the tunnel in the lower part thereof in all portions of the tunnel outside of the heating zone, all of the supporting members being so located and positioned that the tops of the batts form a continuous plane from one end of the tunnel to the other end thereof, said batts being adapted to be moved through the tunnel by a ram.

5. In a tunnel kiln as claimed in claim 4, the combination with the parts and features therein specified, of refractory round rods constituting part of the refractory supporting members in the heating zone, and the batts having grooves in the underside thereof and resting upon said round refractory rods with the rods located in the grooves.

6. In a tunnel kiln as claimed in claim 5, the combination with the parts and features therein specified, of the further feature that the batts are made of silicon carbide and the refractory round rods are made of alumina.

7. A tunnel kiln comprising a refractory structure forming a long straight tunnel, said tunnel being divided into a preheating zone, a heating zone and an annealing zone constituting parts of said tunnel in the order named from the entrance end to the exit end, said tunnel being further divided between top and bottom in all of said zones into an upper portion and a lower portion,

a continuous succession of flat refractory batts extending in a plane through all of said zones and constituting the dividing means, a long line of supports for the batts on each side of the tunnel and well above the bottom thereof, the supports in the heating zone including a pair of lines of stationary refractory cylindrical rods upon which the batts rest and slide, a vault in the upper portion of the heating zone, a trench in the lower portion of the heating zone, and embrasures in the heating zone on either side of the batts and the cylindrical rods upon which they rest and slide, a bank of silicon carbide electrical rod resistors in the vault extending across the upper portion, a bank of silicon carbide electrical rod resistors in the trench below the batts and extending across the lower portion, and banks of silicon carbide electrical rod resistors in the embrasures extending from the top of the kiln to the bottom thereof, said flat refractory batts being adapted to be pushed through the tunnel by a ram.

8. A tunnel kiln comprising a refractory structure forming a long tunnel, said refractory structure having a groove from end to end of the tunnel on each side thereof in the lower part of the tunnel, said grooves being straight and parallel, a continuous succession of stationary rods in the grooves, said tunnel having a heating zone intermediate its ends, a set of rollers in straight end to end relation in portions of the tunnel outside of the heating zone alongside of the rods on one side, a second set of rollers in straight end to end relation also in portions of the tunnel outside of the heating zone alongside of the rods on the other side, said sets of rollers being parallel to each other, a continuous succession of flat refractory batts in the tunnel extending without gap between them from one end to the other end thereof and said batts being in a common plane, said batts being supported in the heating zone by the rods and some of the batts outside of the heating zone being supported by the rollers, said rods in the heating zone being refractory.
